UNITED STATES PATENT OFFICE.

ALEXANDER URBAN, OF NEW YORK, N. Y., ASSIGNOR OF ONE-HALF TO AUGUST FUCHS,
OF NEW YORK, N. Y.

RAIL-JOINT.

1,199,324.

Specification of Letters Patent. Patented Sept. 26, 1916.

Application filed February 29, 1916. Serial No. 81,109.

To all whom it may concern:

Be it known that I, ALEXANDER URBAN, a subject of the Emperor of Austria-Hungary, and resident of New York, in the 5 county of New York and State of New York, have invented certain new and useful Improvements in Rail-Joints, of which the following is a specification.

This invention relates to improvements in 10 fastenings for rails, such as are used in track construction, the fastenings being adapted particularly for use at the joints where one rail abuts against another.

The principal object of the invention is to 15 provide means whereby such joints are firmly held upon the ties or sleepers so that the adjoining rails will be maintained in accurate alinement.

Another object is to provide such devices 20 which are particularly easy to apply, and which can be removed when desired, without the usual labor involved.

These and other objects, such as simplicity of parts, and low cost of manufacture, are 25 attained by the novel construction of parts hereafter described, and shown in the accompanying drawings, forming part of this invention, and in which:—

Figure 1 is a perspective view, showing a 30 section of track, and indicating the application of the invention. Fig. 2 is a plan view showing a rail joint to which the devices are applied, drawn to an enlarged scale, and Fig. 3 is a partial end elevation and sec- 35 tional view, the section being taken on line 3—3 of Fig. 2.

In the drawing, the track rail head is indicated by the numeral 10, the stem 11 and the base 12, while the ties have the numeral 40 14 appended to them.

In carrying out the invention, the ties are preferably recessed on opposite sides of the rail center, and have secured in them blocks 45 15, held firmly down by spikes 16, or other preferred fastenings, such as are commonly used. Thus a double means is provided to maintain the block in a rigid position, both laterally and longitudinally with relation to the tie 14.

50 The front ends of the blocks 15 are formed

with concave faces 18, against which rest the outer convex portions 20 of the rail clamps, the rounded part being a continuation of the flange 21, which is formed integrally with a vertical plate 22, adapted to 55 make contact below the head of the rail, as at 23, and also with the upper portion of the rail base at 24, whereby the rail is stiffened and supported, the same performing the function of a fish plate. Extending between the flange 21 and vertical element 22 are integrally formed braces 25, so that a stiff and rigid structure is presented. These clamps are secured, in addition to the rounded portion 20, by screw bolts 26 or other preferred fastening means, and are so adjusted with reference to the rail ends, that an equal length of each rail is held between the clamps which are used as clearly indicated in the several views.

In operation, the blocks 15 are inserted in the recessed ties and spiked rigidly in place; the clamps are then entered so that the part 20 makes contact with the recess 18, the vertical part 22 then swung into position upon opposite sides of the rail, pivoting against the blocks 15, which hold them closely in engagement with the rail stem as will be apparent. The bolts 26 may then be inserted, binding and clamping the entire structure rigidly together and holding the ends of the rails so that they cannot move laterally.

Having thus described my invention, what I claim as new and desire to secure by Letters Patent, is:—

1. In a rail clamping device, the combination with a pair of rails and sleepers upon which said rails rest, of a pair of blocks recessed in said sleepers upon opposite sides of the rails, a pair of clamp brackets suited to the stem of said rail, contacting with the base and head thereof, flanged elements extending from said brackets having a curved outer head contactable with the said blocks and brace elements extending integrally between said flange elements and said brackets.

2. In a rail clamping device, the combination with a pair of vertical plates suited to the stem of the rails and extending be-

tween the base and head thereof, horizontal extensions formed with said plates having a curved outer edge, triangular braces extending between said plates and extensions, 5 means for securing said extensions to the ties, and blocks rigidly set in said ties having a concave face adapted to make contact

with the curved edge of said flanged element in the manner of a hinge.

Signed at New York, in the county of 10 New York, and State of New York, this 10th day of February, 1916.

ALEXANDER URBAN.

Copies of this patent may be obtained for five cents each, by addressing the "Commissioner of Patents, Washington, D. C."
